UNITED STATES PATENT OFFICE.

LOUISE B. STRANG AND CHARLES C. POLLOCK, OF SEATTLE, WASHINGTON.

BRUSH.

1,297,272.

Specification of Letters Patent. Patented Mar. 11, 1919.

Application filed December 1, 1917. Serial No. 204,918.

To all whom it may concern:

Be it known that we, LOUISE B. STRANG and CHARLES C. POLLOCK, citizens of the United States, residing at Seattle, in the county of

King and State of Washington, have invented new and useful Improvements in Brushes, of which the following is a specification.

This invention relates to a brush which is primarily intended for washing dishes, although the construction and shape of the brush is such that it may be advantageously employed for washing other articles and surfaces when desired.

10 The primary object of the invention is to provide a brush of this character which is not only so shaped as to facilitate the dislodging of matter from grooves and depressions in the surfaces to be washed, but is provided with an elastic scraping band which is so connected with the brush that it may be adjusted on the brush toward or away from the support to be cleaned, thus increasing the efficiency of the brush for the purpose stated.

15 Another object of the invention is to provide a brush in which a cap not only serves as a cover for the brush head but assists in maintaining the elastic scraping band upon the brush.

20 A further object of the invention is to provide the brush with a handle which is so connected with the brush that through the adjustment of the handle upon the brush the scraping band may be firmly wedged between the cap and brush body.

25 With these and other objects in view, the invention resides in the novel combination and arrangement of parts, which will be hereinafter described and particularly pointed out in the claims.

30 The preferred embodiment of the invention has been illustrated in the accompanying drawings, although no restriction is necessarily made to the precise details of construction therein shown, as changes, alterations, and modifications within the scope of the claims may be resorted to when desired.

In the drawings:—

35 Figure 1 is a perspective view of a brush constructed in accordance with the invention.

40 Fig. 2 is a longitudinal section therethrough.

Fig. 3 is a bottom plan view of the brush.

Fig. 4 is a perspective view of the brush head of which the cap and handle have been removed.

Like characters of reference denote corresponding parts throughout the several views in the drawing.

Referring now to the drawing in detail wherein a brush for the purpose set forth is shown constructed in accordance with the invention with the brush including a semi-oval shaped brush head 5 which may be formed from any material suitable for the purpose. The brush head 5 is convex at its upper side and has formed therein adjacent its larger end a vertical opening 6. The opening 6 which serves as a soap chamber 70 has arranged therein a cylindrical reticulated soap holder 7 which in this instance has been shown formed from wire netting. The soap holder 7 has an open top and terminates at its upper end a laterally extending flange 8 which rests upon the curved top of the brush head 5 and supports the soap holder 7 within the opening 6.

Connected with the brush head 5 in the usual manner to extend below the bottom thereof are tufts of bristles with the tufts arranged in a continuous row 9 which is spaced from the sides of the bottom of the brush head. Other tufts of bristles connected with the brush head 5 are arranged in rows 10 which extend transversely of the bottom of the brush head.

45 An elastic scraping band 11 has the brush head arranged in the opening therein so that the band 11 will extend a considerable distance below the bottom of the brush head 5 and owing to the resiliency of the material from which the band is formed may be adjusted on the brush head to cause the lower edge of the band to lie flush with the bottoms of the tufts of bristles 9 and 10.

The brush head 5 is provided with a resili- 50 ent cap 12 preferably of sheet metal, which corresponds in shape to the brush head 5 and overlies the scraping band 11 is preferably 100 of rubber, for a portion of its length and assists in maintaining the band upon the head 5.

The brush head 5 is provided with a threaded stem 13 which extends above the 105 curved top of the brush head and is passed through a suitable opening in the cap 12. A knob 14 which serves as a handle for the

brush is threadedly engaged with the extending portion of the stem 13 and bears against the top of the cap 12, so that by turning the knob on the stem 13 the brush head may be drawn within the cap to firmly wedge the scraping band between the brush head and cap.

By mounting the scraping band upon the brush head in the manner described and 16 providing the brush with the cap 12 and knob 14 it is obvious that a scraping band may be moved toward or away from the surface to be cleaned as desired or held in adjusted position upon the brush head of the 15 cap 12 which also serves to close one end of the soap holder 7.

From the foregoing description taken in connection with the accompanying drawing it is apparent that a brush for the purpose 20 set forth has been provided which has a scraping band so connected therewith that the band not only increases the efficiency of the brush as a scrubbing instrument but may be easily and quickly replaced when the occasion requires.

Having thus described the invention, what is claimed, as new, is:—

1. In a brush, the combination of a head having a convex upper side, a concave cap 30 superimposed upon said head, a scraping band interposed between and depending from the head and the cap, and means for

clamping the cap on the head and against the band.

2. In a brush of the class described, a 35 brush head, an elastic scraping band on the brush head extending below the same, and a cap into which said brush head fits engaging said scraping band.

3. In a brush of the class described, a 40 brush head, a soap chamber therein, an elastic scraping band into which said brush head extends, said band extending below said head, a cap in which said brush head is received engaging said scraping band, a stem 45 on said brush head extending through said cap, and a handle mounted to turn on said stem and bearing against said cap.

4. In a brush, the combination of a head convex at its upper side, bristles carried by 50 and depending from said head, a soap holder of foraminous character carried in the head and open at its upper end, a concave cap positioned on the head and closing the upper end of the receptacle, a scraping band interposed and secured between the head and the cap, a stem extending through the head and cap, and combined handle, and clamping means mounted on said stem above the cap.

In testimony whereof we affix our signatures.

LOUISE B. STRANG.
CHARLES C. POLLOCK.
